CLAIM

The ornamental design for a pedestal base for cookware, as shown and described.

DESCRIPTION

FIG. 1 is a top perspective view from above the “pedestal base for cookware”, showing my new design;

FIG. 2 is a top plan view thereof;

FIG. 3 is an elevational view thereof;

FIG. 4 is a bottom perspective view thereof; and,

FIG. 5 is a bottom plan view.

The broken lines in FIGS. 1–5 are for illustrative purposes only, depicting the environment of the new design, forming no part thereof as claimed.
